United States Patent Office

Des. 226,519
Patented Mar. 20, 1973

226,519

BOTTLE

Howard Cooper, Suite 7707, 175 E. Delaware,
Chicago, Ill. 60611

Filed Jan. 8, 1971, Ser. No. 105,143

Term of patent 14 years

Int. Cl. D9—01

U.S. Cl. D9—28

FIG. 1 is a front view of a bottle embodying my new design;

FIG. 2 is a back view thereof;

FIG. 3 is a top view thereof; and

FIG. 4 is an enlarged cross-sectional view of a portion of the bottle shown in FIG. 1 taken along the line 4—4 thereof.

I claim:

The ornamental design for a bottle, substantially as shown.
